UNITED STATES PATENT OFFICE

FREDERICK H. WAGNER, OF BALTIMORE, MARYLAND, ASSIGNOR TO THE BARTLETT HAYWARD COMPANY, OF BALTIMORE, MARYLAND, A CORPORATION OF MARYLAND

MEANS FOR HANDLING SEALING LIQUID FOR GAS HOLDERS

Application filed August 19, 1927. Serial No. 214,162.

This invention pertains to an improved apparatus for the handling of the sealing medium employed in conjunction with the so-called waterless gas holder, such as is disclosed for instance in Letters Patent to Jaggschitz No. 1,275,696, dated August 13th, 1918.

As will be seen upon reference to said patent, a liquid is employed as a sealing medium between the movable piston or closure and the wall of the holder, such liquid being in most instances tar. Tar as a sealing medium has been found satisfactory in most instances, but under certain conditions some difficulty in its utilization obtains:—this due 10 to the nature of the tar, climatic conditions, and other factors.

Generally speaking, the main difficulty arises because of the fact that the tar emulsifies with water of condensation or light oils within the system and by reason of such emulsification its effectiveness as a sealing medium is lowered. Further, it is common 20 in the installation of a waterless gas holder to employ pumps, which pumps, particularly 25 where they are of the gear type, tend to emulsify the liquids and hence lower the effectiveness of the tar.

The main object of the present invention is to provide a system whereby all pumps, 30 as such, are done away with and to employ air pressure to force the tar into the upper portion of the holder where it passes into the channel formed around the closure or piston of the holder which distributes it against the 35 face of the wall of the holder.

A further object of the invention is to provide an automatic system whereby supervision or attendance on the part of the operator is minimized or, in other words, to 40 have the system automatic.

A still further object of the invention is to provide means whereby the tar or other sealing fluid, if it becomes emulsified, may be passed through a de-emulsifier prior to its 45 being forced back again to the upper portion of the holder.

With these and other objects in view, reference is had to the annexed drawing wherein there is shown in the figure so much of a system for handling the tar as is necessary to a

full understanding of the invention parts being shown in section and the rest in elevation.

In said figure 1 denotes the base of a waterless holder of the type above mentioned and 2 a portion of the shell or wall thereof.

55

Sealing fluid or tar collects in a trough in the lower portion of the gas holder as it passes down along the inner wall thereof from the closure and is drawn off therefrom from time to time and recirculated back to 60 the upper portion of the holder where it is discharged into an annular channel 3 located at the upper portion of the holder from which it is conducted back to the trough which is associated with the piston or closure C in any 65 suitable or convenient manner. This is common practice. In the present instance, however, the tar which collects in the trough at the bottom of the holder passes outwardly therefrom through a pipe 4, having an inverted mouth, into a tank 5, the lower end of the pipe extending well down toward the 70 bottom of the tank.

A weir 6 is located in the pipe 4 thus keeping the inner portion of the pipe full of tar 75 at all times. The flow of the tar through the pipe is controlled by a valve 7.

It will be appreciated, of course, that any number of these tanks 5 may be spaced around the base of the holder and suitable pipes as 4 80 will extend thereto from the holder as indicated in the drawing.

A pressure equalizing pipe 8 extends from the chamber, in which the weir 6 is mounted, to the interior of the holder thus permitting 85 the tar to flow through the pipe 4 when the valve 7 is open.

A pipe 9 extends from the lower portion of the tank 5 upwardly and discharges, as indicated at the upper right hand part of the 90 figure, into the holder above the movable piston or closure.

A second tank 5^a, similar to tank 5, will preferably be employed in conjunction with the latter, and such other tanks as 5 which 95 may be placed about the holder. Tank 5^a is not, however, connected to the bottom of the holder but is in communication with pipe 9 through a branch pipe 10, said pipes being provided respectively with hand operated 100

valves 11 and 12. By closing 11 and opening 12 flow of tar directly to the channel 3 is stopped and the tar caused to pass through pipe 10 to a de-emulsifier 13 of an approved type wherein the emulsified tar is separated into its constituent elements as tar and water. The separated and purified tar passes through a pipe 14 into the tank 5^a, this assuming that the manually controlled valve 15 and the automatically controlled valve 16 are both open. The purified tar entering tank 5^a may be forced by air pressure, in a manner to be shortly set forth, through a pipe 17 to the distributing channel 3. It will of course be understood that where the tar (or other sealing liquid) is not emulsified the de-emulsifier 13, and as a consequence tank 5^a, will be cut out, this by closing valves 12 and 15 and opening valve 11.

It is designed to have air under compression at all times in order that the tar may be forced upwardly through pipe 9, (or pipes 9 where a plurality of tanks as 5 are employed) or upwardly through pipe 17. To this end I provide a compressed air reservoir 18 and automatic means of any approved type for maintaining the requisite pressure therein.

A pipe 19 opens into the tank from a compressor (not shown) and leads 20 and 21 extending to the compressor motor are connected to the terminals of a solenoid controlled switch 22 adapted, when the switch is closed, to connect the leads with the power lines 23 and 24.

Extending upwardly from reservoir 18 is a cylinder 25 in which is mounted a piston 26, the rod 27 whereof extends upwardly and is connected with a switch 28 which controls the current passing from the main line 23 and 24 through leads 29 and 30 leading to the winding of the solenoid of switch 22. A spring 27^a associated with rod 27 tends to force the rod and piston downwardly and to open the switch 28.

As will be readily understood, when the air pressure within the reservoir 18 falls below the desired amount the compressor will be automatically thrown into operation and continue to function until the pressure is re-established within the reservoir.

Extending from the reservoir is a pipe 31 provided with a branch 32 which extends into the upper portion of the tank 5. The branch 32 is provided with a valve 33 and a valve 34 is also provided in a branch line or vent pipe 35 extending from the branch 32 between the tank and the valve 33. Similarly the tank 5^a is connected to the pipe 31 and the similar parts are lettered the same with the exponent "a" added thereto.

The valves 33 and 34 are interconnected so that as one is opened the other is closed. The same is true of the valves 33^a and 34^a. To this end I provide a piston rod 36 suitably guided and having links 37 and 38 connected to said rod and respectively to the valves 33 and 34. Rod 36 is connected to a piston working in an air cylinder 39 having air pipes 40 and 41 opening into the opposite ends thereof and leading to lines 42 and 43. Said pipes 42 and 43 are connected at their lower ends in the hook-up as shown with the opposite ends of an air cylinder 44, a piston rod 45 whereof is connected to the valve 7. The lines 42 and 43 at their opposite ends extend into a valve casing 46 in which is mounted a slide valve 47 actuated and controlled by a solenoid 48. The valve casing 46 is provided with a third port, intermediate the connections of the lines 42 and 43, which third port is in communication with an air line 49 connected by a branch 50 into the pipe 31 so that air under pressure is always present in said line 49—50. This arrangement is duplicated in connection with the tank 5^a and the valve 16, heretofore referred to, is connected with the piston rod 45^a of the air cylinder 44^a.

Mounted in the tank 5 is a float 51, the float being attached to a rod 52 which latter passes through suitable guides 53 and 54. The rod at its upper end carries two pins 55 and 56 adapted to cooperate with a lever or arm 57 connected to the fulcrum 58 of a mercoid switch 59 located within the tank. The terminals of the switch, which are adapted to be bridged by the mercury when the switch is in its elevated position or that shown in full lines, are connected to leads 60 and 61, the former including the winding of the solenoid 48 and both of said leads being connected to the power lines 23 and 24. The same float and switch installation is shown in connection with the tank 5^a and similar parts are similarly lettered with the exponent "a" added thereto.

A manually controlled switch 62 is placed in the lines 23 and 24 so that by opening said switch the lines to the compressor will be broken and hence the apparatus as a whole shut down owing to the fact that the air pressure in the reservoir 18 will fall.

It is to be understood that the showing is more or less diagrammatic.

In operation, and assuming the tank 5 is to be called upon to supply the necessary tar or sealing liquid to the channel 3 and it being assumed that air under sufficient pressure is present in the reservoir 18 and that the valve 33 is open and 34 closed, air under pressure will be exerted upon the tar within the tank and as a consequence the tar will be forced upwardly through the pipe 9, the valve 11 at such time being open, and the valve 12 closed, the tar will pass into the channel 3. This, of course, assumes that the circuit is closed by the switch 59 so that the valve 47 will be elevated and air under pressure allowed to pass through line 49 and line 42 to the upper end of the cylinder 44 forcing the rod 45 downwardly and closing valve 7.

At this time the bottom of the cylinder 44

will be vented as will also the bottom of the cylinder 39, hence the valve 33 will be open and the valve 34 closed as above specified. In other words, when the valve 7 is closed the valve 33 is open and the valve 38 closed.

5 From this it will be seen that when the valve 7 is closed the valve 33 is open and the vent through the pipe 35 is stopped by the closing of the valve 34, hence the air pressure acting upon the top of the tar in the tank 5 will force the tar upwardly through the pipe 9, which at that time is the only escape for the tar.

As the tank is partially emptied the float 51 drops and the guide rod is lowered therewith. The pin 55 coming into contact with the arm or lever 57 rocks the switch 59 and breaks the circuit de-energizing the coil 48 and thereby causing the valve 47 to shift, venting pipe 42, and likewise 40, and allowing pressure to pass from pipe 49 through the branches 41 and 43 to the lower ends of the respective cylinders 39 and 44 thereby actuating the piston rods 36 and 45 and securing a reversal of the position of the various valves. At such time valve 7 is open, the vent valve 34 open, and the inlet air valve 33 closed. Under these conditions tar will flow into the tank 5 by gravity and will continue so to flow until the float 51 is again raised and the switch 59 brought into action.

30 When, as above noted, the tar becomes emulsified, through one or another reason, it may be caused to flow from the tank 5 to the de-emulsifier 13, valve 11 being closed and valve 12 open. Valve 15 will likewise be open and the separated or cleaned tar will pass from the de-emulsifier through pipe 14 into the tank 5^a. At such times the valves, as described in connection with the tank 5, will be caused to function in the same manner through the rising and lowering of the float 51^a in the tank 5^a, the float causing the switch 59^a to function as described in connection with the tank 5.

45 It will, of course, be appreciated that when the tar has been brought back to its normal condition the tank 5^a and the de-emulsifier may be cut out.

What is claimed is:

50 1. In combination with a gas holder having a movable closure adapted to be sealed by a liquid which trickles down the walls of the holder and collects at the base thereof; means for withdrawing such liquid as gathers in the lower portion of the holder; means for applying air under pressure to such withdrawn liquid to force the same to the upper portion of the holder; and means operating in timed relation with the air applying means for cutting off the withdrawal of the liquid from the holder during the application of such pressure.

60 2. In an apparatus for elevating a sealing liquid to the upper portion of a gas holder having a movable closure adapted to be sealed

by such liquid, the combination of such holder; a tank; a valved conduit extending from the lower portion of the holder to said tank; a conduit extending from the lower portion of said tank to the upper part of the holder; a valved pipe extending from a source of air under compression to the upper portion of the tank; a valved controlled vent for said tank; and means controlled by the height of the liquid in the tank for actuating the valves in proper sequence. 70 75

3. In combination with a gas holder having a movable closure adapted to be sealed by a liquid; a tank located adjacent the base of the holder; a pipe extending from the base of the holder to the lower portion of the tank serving to withdraw the liquid from the holder to the tank; a valve therein; a pipe leading from the tank to the upper portion of the holder; a source of air under compression; a conduit leading therefrom to the upper portion of the tank; a valve in said conduit; an air vent for the tank; a valve controlling said vent; and means controlled by the rise of the liquid within the tank for simultaneously closing the first and last named valves and opening the valve in the air conduit, and likewise securing a reverse operation of said valves when the level of the liquid falls within the tank. 80 85 90

4. In an apparatus for elevating a sealing liquid to the upper portion of a gas holder having a movable closure adapted to be sealed by said liquid, the combination of such holder; a tank; a conduit extending from the lower portion of the holder to said tank; a valve for opening and closing said conduit; a pipe extending from the lower portion of the tank to the upper portion of the holder; a source of air under compression; a conduit leading from said source to the upper portion of the tank; a valve for opening and closing said conduit; an air vent for said tank; a valve for controlling said vent; an air motor interconnected with the air conduit valve and the air exhaust valve; a second air motor connected with the valve controlling the conduit leading from the holder to the tank; air lines connected to the source of air under pressure and to the air motors, aforesaid; a valve for controlling the passage of air to and from said air motors; a float mounted in the tank; an electric switch adapted to be brought into operation by the movement of said float; and an electric motor for controlling the valve located in the air lines leading to the air motors, said motor and electric switch being connected to a common circuit. 100 105 110 115 120

In testimony whereof I have signed my name to this specification.

FREDERICK H. WAGNER.
